TONY LASKA, OF CLE-ELUM, WASHINGTON

INSULATED RAIL JOINT

Application filed July 28, 1930. Serial No. 471,329.

This invention relates to an improved insulated rail joint.

In modern railway signaling, the track is divided into what are known as block sections and these sections are necessarily insulated from each other to permit proper functioning of the signals. In the past, means of various types have been employed for this purpose, but it has been found that such means are either too delicate in structure to withstand the repeated pounding of the wheels of a train passing thereover, or they incorporate so many parts that they are impractical.

15 One object of the present invention is, therefore, to provide an improved insulated rail joint which will be efficient and which will incorporate a minimum number of working parts.

20 Another object of the invention is to provide a device of this character wherein the insulating material will abut only one of the meeting ends of the rail.

A further object of the invention is to provide an insulated rail joint wherein the fish plates are recessed at corresponding ends to accommodate the shims of insulating material so that said shims will lie flush with the opposite corresponding ends of the fish plates.

25 Other and incidental objects of the invention not mentioned in the foregoing will be apparent during the course of the following description.

The invention is illustrated in the accompanying drawing, wherein:

Figure 1 is a perspective view of the device.

Figure 2 is a horizontal sectional view of the device.

40 Figure 3 is a vertical sectional view on the line 3-3 of Figure 2, looking in the direction indicated by the arrows.

Figure 4 is a fragmentary perspective view showing more clearly the reduced portion of one of the fish plates.

Referring more particularly to the drawing, I have shown the meeting end portions of railroad rails 20 and 30 having treads 1, webs 2, and flanges 3.

45 The improved insulated rail joint comprises-

ing the subject matter of the present invention includes fish plates having angularly disposed vertical and lateral flanges 4 and 5, the former of which are provided with longitudinal channels 6 which confront the rail webs, while the latter flanges overlie the flanges 3 of the rails. As seen best in Figure 4 of the drawing, corresponding end portions of the lateral flanges 5 of the fish plates are recessed or reduced at their lower sides and inner edges substantially half their lengths and the vertical flanges are also reduced at their top edges and inner sides substantially half their lengths, said reduced portions of the lateral and vertical flanges defining shoulders 7 having rounded upper and lower edges. Overlying the reduced end portions of the fish plates are substantially channel shaped insulating shims 8 which are preferably formed of pliable insulating material and are of uniform thickness throughout. The shims abut the shoulders 7 and are provided with webs having relatively narrow top flanges 9 and relatively wide bottom flanges 10. The webs of the shims lie flat against the web of the rail end 20 while the relatively narrow top and relatively wide bottom flanges 9 and 10 are seated between the lower faces of the tread of said rail end and the top edges of the fish plates, and between the flanges 5 of the plates and the adjacent rail flanges 3 respectively.

Extending through the reduced end portions of the fish plates are bolts 9' having nuts 10' screwed thereon, said bolts clamping said end portions of the fish plates to the web 2 of the rail end 20. Surrounding the bolts are insulating sleeves 12 which are formed preferably of pliable fiber. As can be seen more clearly in Figures 2 and 3 of the drawing, the sleeves are carried on the bolts at their medial portions and said sleeves extend through the rail web 2 of the rail end 20 as well as through the shims 8 into the channels 6. These sleeves 12 insulate the bolts 9' from said web. Extending through the fish plates at the opposite end portions thereof are bolts 13 having nuts 14, said bolts clamping said fish plates to the web of the rail end 30. Suitable locking washers may be interposed be-

5   between the nuts and the fish plates for locking
      said nuts in position. Disposed between the
      meeting end faces of the rail ends is a sepa-
      rator 15 which is formed preferably of pli-
      able insulating material and is of uniform
      thickness throughout. The separator sub-
      stantially conforms to the shape of a cross
      section of the rail ends, said separator pre-
      venting the making of electrical contact,
      which might be caused by creeping of the
      rails due to expansion and contraction. As
      seen more clearly in Figure 2 of the draw-
      ing, the shims 8 overlap the edges of the sep-
      arator to prevent possible lateral displace-
      ment thereof.

10   When installing the improved insulated
      rail joint, the separator is first placed in po-
      sition between the meeting end faces of the
      rail ends. One of the shims 8 is then placed
      20 in position in overlying relation to the re-
      duced portion of one of the fish plates. One
      of the bolts 9' is then projected through the
      vertical flange of said fish plate and through
      the shim overlying said plate, when one of
      25 the sleeves 12 is slipped over the outer end of
      said bolt and moved rearwardly on said bolt
      into engagement with the inner face of the
      vertical flange of the fish plate. The fish
      plate is then placed in abutting relation with
      30 the rail ends and, of course, the bolt will ex-
      tend through the web of one of the rail ends
      20. The opposite shim 8 is then placed in
      position on the opposite fish plate in the same
      manner as described in connection with the
      35 first mentioned fish plate. A second bolt 9'
      is projected through the second mentioned
      fish plate and an insulating sleeve similar to
      the first mentioned insulating sleeve is
      slipped over the bolt when said fish plate
      40 is moved into abutting relation with the face
      of the rail web opposite the former fish plate
      and shim. The nuts 10 and 14 are then
      screwed on for tightly clamping the fish
      45 plates and shims in position on the rail ends.
      45 Due to the fact that the shims are formed of
      pliable insulating material, danger of crack-
      ing said shims when tightening up the bolts
      is obviated.

50   Attention is directed to the fact that in-
      asmuch as the shims 8 lie within the recessed
      portions of corresponding ends of the fish
      plates and are disposed flush with the oppo-
      site corresponding ends of the said plates,
      55 it will not be necessary to employ shims of in-
      sulating or of other material to compensate
      for the thickness of said shims 8. It can
      be readily seen, therefore, that the use of a
      large number of working parts is obviated,
      thereby permitting greater efficiency and
      60 cheaper manufacture.

60   What is claimed is:

65   An insulated rail joint comprising mating
      rail ends having bolt-receiving openings
      formed in the webs thereof, a separator of in-
      sulating material interposed between said

70   rail ends for the entire height thereof, oppo-
      sitely disposed angle bars connecting the rail
      ends and provided with bolt-receiving open-
      ings of less diameter than the openings in
      the rail webs and registering therewith, se-
      curing bolts extending through said regis-
      tering openings, channel shaped shims in-
      dependent of the separator and former of in-
      sulating material interposed between the
      angle bars and webs of the rail ends and over-
      75 lapping and bearing against the adjacent
      side edges of the insulated separator at the
      webs of said rail ends, and insulating sleeves
      of a length equal to the distance between
      80 the inner faces of the angle bars surrounding
      certain of the securing bolts and extending
      through the adjacent openings in the webs
      of the rail ends and through said insulating
      shims with their ends projecting beyond the
      shims and bearing snugly against the inner
      85 faces of the angle bars around the adjacent
      securing bolts.

90   In testimony whereof I affix my signature.
      TONY LASKA. [L. s.]
